UNITED STATES PATENT OFFICE.

OTTO C. BUSS, OF HAVRE, FRANCE.

JET-CONDENSER.

1,179,369.

Specification of Letters Patent. Patented Apr. 11, 1916.

Application filed May 23, 1910. Serial No. 562,912.

To all whom it may concern:

Be it known that I, OTTO C. BUSS, a citizen of the Republic of Switzerland, and a resident of Havre, France, have made a 5 new and useful Invention in Jet-Condensers, of which the following is a specification.

This invention relates to condensers and more particularly to condensers of the ejector type.

10 In British Patent 8452 of 1905, Maurice Le Blanc discloses a novel fluid translating device applied to an ejector condenser, and an object of this invention is to produce an improved ejector condenser utilizing 15 said Le Blanc translating device. This as well as other objects which will readily appear to those skilled in this art I attain by means of the device described in the specification and illustrated in the drawings accompanying the same and forming a part 20 hereof, and throughout which similar elements are denoted by like characters.

Figure 1 is a view in sectional elevation of a device embodying this invention taken 25 on line 1—1 of Fig. 3; Fig. 2 is a view in elevation with a portion thereof taken in section on the line 2—2 of Fig. 1; Fig. 3 is a view of the device partially in plan and partially in section on the line 3—3 30 of Fig. 1; Fig. 4 is a top plan view of the device shown in Fig. 1; Fig. 5 is a view in sectional elevation of a modification of this invention; Fig. 6 is a view in elevation with a portion thereof shown in section and taken on line 6—6 of Fig. 5; Fig. 7 is a view partially in plan and partially 35 in section on the line 7—7 of Fig. 5 looking down upon the device shown in Figs. 5 and 6.

40 In carrying out this invention I employ the fluid translating device invented by Maurice Le Blanc and disclosed in said British patent. This consists of a rotatable impeller provided with an annular row of 45 blades and a water or other liquid distributor having a delivery nozzle for delivering or distributing water to a number of the blades of the impeller in such a way that, at any given instant water is delivered to less 50 than the total number of blades, thereby making the impeller a partial injection or partial influx impeller, or it may be described as a partial ejection or partial efflux impeller. As shown in Figs. 1 to 5, water is

delivered to not more than three of the 55 blades of the impeller at any given instant. The water delivered by the distributor to the impeller is minutely subdivided on account of the high rotational speed given to the impeller by outside means, such as a 60 motor or steam turbine, and projected therefrom in the form of films or leaves of relatively high velocity.

I have found that when Le Blanc's fluid translating device is utilized in a condenser 65 such as disclosed in said British patent while it is highly efficient as a condenser it is not capable of taking care of the non-condensable vapors which enter the condenser. In the condenser of the said British 70 patent the leaves or films of liquid projected by the impeller are projected or discharged into a relatively large chamber and therein are allowed to spread out so as to present a greatly extended surface for condensing purposes. Condensers of this type 75 are largely used in connection with steam turbines as well as in connection with reciprocating steam engines and while turbines are not as liable to have air leaks as reciprocating engines the piping between the turbine and the condenser is always more or less a source of trouble in this regard.

The device illustrated in Figs. 1 to 4 consists of a body portion 8 having formed 85 in one side thereof a chamber for the rotatable impeller 9. The chamber is provided with end plates 10 and 11 through which the shaft 12 of the impeller 9 passes. End plate 10 is provided with a stuffing box 90 13 for the shaft, and end plate 11 is extended so as to form a water chamber 14 having a flanged opening 15 and is also provided with a stuffing box 16 for said shaft.

95 Between the body portion 8 and end plate 11 a flange of a water distributor 17 is adjustably secured and said distributor is formed so that it projects within the ring of impeller blades 18 which are arranged in 100 an annular row projecting from one side of the impeller disk. The distributor is provided with an outlet nozzle 19 which by means of turning the distributor 17 may be adjusted to the proper position desired 105 in order that water may be fed or distributed to the blades of the impeller at just the proper point.

22
Bearings 20 and 21 are provided for the impeller shaft 12 and while bearing 20 is carried on a bracket 22 secured to end plate 10, bearing 21 is carried on the extension of 5 end plate 11. Impeller shaft 12, it will be understood, is adapted to be rotated at the desired speed by any suitable means such as a reciprocating engine, an electric motor or a steam turbine and the shape and angular- 10 ity of the blades, as well as the position of the nozzle 19, will be determined by the peripheral speed given to the impeller by the motor which drives it.

15 Body portion 8 is provided with a top or cap member 23 which has an inlet 24 arranged in the side thereof and an inlet covered by cap 25 arranged in the top. This is done in order that the condenser may be connected in either way desired.

20 Body portion 8 is secured to a bed plate 26 which has downwardly projecting walls 27. Below the body portion 8 and bed plate 26 and within the walls 27 a converging tube or collecting and combining tube 28 is located, and to the lower end of the walls 27 a divergent transformer or diffuser 29 is secured. Between the outlet end 30 of the collecting tube 28 and the inlet to the diffuser 29, a steam cone 31, for the purpose of prim- 30 ing the condenser, is located and this cone which is formed so as to leave an annular passage 32 between it and the diffuser shell is adapted to be supplied with steam through an inlet 33.

35 All this portion of the device thus far described, it will be found, is substantially the same as the device shown in the Le Blanc British patent before referred to and I have improved said device by adding thereto a 40 device such, for example, as a collecting cone 34 which by means of web members 35 is supported by the walls of the collecting tube 28 so that its top lies just below distributor nozzle 19.

45 For want of a better descriptive term, I will, throughout the further description of the apparatus refer to the cone 34 as a stabilizer for the reason that it insures a more uniform operation of the apparatus 50 and causes the condenser to hold a more stable or uniform vacuum.

55 Operation: Assuming that either the inlet 24 or the inlet shown closed by the cover plate 25 is connected to a source of fluid or steam to be condensed; that the water inlet 15 is connected to a suitable source of water supply; that the steam inlet 33 is connected by means of a valved connection to a suitable source of steam supply; and that the 60 impeller 9 is rotated at the desired speed in a direction such that its blades 18 move downwardly past the discharge end of the nozzle 19. Under such conditions, priming, by admitting steam to the port 33, will fill the distributor chamber with water. If the water

is delivered under pressure to the distributor chamber, the priming will not be necessary. This will cause water to rise and fill the distributing chamber and flow out through distributor nozzle 19. The blades carried by the impeller moving past the distributing nozzle 19 will cut off the water, so to speak, and project it in the form of films into and across stabilizer 34 and these films of water will move at high velocity through 70 the stabilizer, and on account of its convergence, will be compressed into a more or less compact stream which will issue from the outlet thereof and move toward and through the collecting tube 28 in the form of 75 a stream having a high velocity. The stream on issuing from the outlet 30 of collecting tube 28 passes into and through the diffuser 29 and therein the fluid velocity is transformed into pressure in the well-known manner, on account of the divergence of the 80 walls of the diffuser. The steam within the body 8 will be condensed in a two-fold manner; that is, a portion of it will be condensed by means of the films of water projected into the stabilizer and a portion thereof will be condensed by contacting with the stream issuing from the outlet of the stabilizer and traversing the collecting tube 28. The non-condensable vapors within the body 85 portion 8 will be confined between the leaves or films of water and will be carried by them through the stabilizer and into and through the tube 28 and will be discharged 90 therefrom into the diffuser in which the velocity thereof will be transformed into pressure. A portion of the non-condensable vapors, of course, will be carried through the tube 28 and into the diffuser by means of the 100 friction between the stream made up of the leaves of water and the non-condensable vapors. As the tension of the fluid in the immediate vicinity of the inlet of the stabilizer will be less than the tension of the 105 fluids in the other portions of the body 8, 110 the non-condensable vapors as well as the condensable vapors, will have a tendency to flow into the stabilizer, and, will by means of the leaves of water, be carried there-through and compacted by the walls of the 115 stabilizer into a more or less solid stream.

While the condenser shown in Figs. 1 to 4 is highly effective for use in connection with steam turbines, it is desirable to modify the construction somewhat where the condenser 120 is to be utilized in connection with reciprocating steam engines, and such a modification I have illustrated in Figs. 5 to 7.

As it is ordinarily necessary for a condenser operating in connection with reciprocating steam engines to handle more air than condensers operating in connection with steam turbines, two stabilizers 36 and 37 connected together by means of a supporting web structure 38, are utilized. These 125 130

are arranged axially in line and adapted to operate in series. The leaves of water projected by the impeller are projected into and across stabilitor 36, and, after being compacted therein into a more or less solid stream, pass through stabilitor 37 and then through a combining tube 39, of slightly different form than combining tube 28. By means of these two stabilitors 36 and 37, the stream issuing from the upper stabilitor 36 is kept in contact with the fluids within body portion 8 for a longer time and in this manner I am enabled to handle more non-condensable vapors than by the use of a single stabilitor.

In accordance with the provisions of the patent statutes, I have described the principle of operation of my invention, together with the apparatus which I now consider to represent the best embodiment thereof, but I desire to have it understood that the apparatus shown is only illustrative and that the invention can be carried out by other means.

What I claim is:

1. In a condenser, a chamber provided with an inlet for fluid and a converging walled tubular outlet, means employing a partial efflux, rotatable device arranged for delivering liquid at relatively high velocity in a sub-divided state into said chamber between the inlet and outlet thereof, means communicating with said outlet for transforming fluid velocity into pressure, and a cone suspended in said chamber so as to receive the liquid delivered by said device.

2. In a condenser, bladed rotatable means for delivering liquid to the interior of the condenser, a combining tube, means aligned with said tube for transforming fluid velocity into pressure, and a stabilitor for receiving and collecting liquid delivered by said rotatable means.

3. In a condenser, a chamber provided with an inlet for fluid and a converging walled outlet, means employing a rotatable device arranged so as to deliver liquid in the form of films or leaves into said chamber between the inlet and outlet thereof, a diffuser in communication with said outlet and a stabilitor suspended within said chamber in such a manner as to receive the liquid delivered by said device.

4. In a condenser, the combination of a combining tube, a diffuser communicating therewith, a partial ejection rotatable device for delivering a liquid stream into the interior of the condenser and through the combining tube, and a stabilitor for receiving liquid delivered from said device and for delivering the liquid so received to said combining tube.

5. In a condenser, a combining tube, a diffuser, a rotatable bladed device and means located within the periphery of said device for distributing liquid to a number of the

blades thereof less than the total number at any instant, and a stabilitor suspended within said chamber.

6. In a condenser, a chamber provided with an inlet for fluid and an outlet, means arranged so as to deliver liquid at a relatively high velocity in the form of films or leaves into said chamber between the inlet and outlet thereof, and a stabilitor suspended within said chamber for receiving said liquid and delivering the same to said outlet.

7. In a condenser, bladed rotatable means for delivering liquid thereto, a combining tube, means in line with said combining tube for transforming fluid velocity into pressure and at least one stabilitor suspended within said combining tube for collecting the liquid delivered by said device.

8. In a condenser, a condensing chamber, a rotatable bladed means for delivering liquid, moving at a high velocity to said chamber, means for transferring fluid velocity into pressure, and two stabilitors operating in series for collecting liquid delivered by said rotatable means and for delivering it to said velocity transforming means.

9. In a condenser, a condensing chamber having a fluid inlet and a fluid outlet, means for projecting a stream of substantially flat, separate liquid films through the chamber in a direction approximately at right angles to the plane of each separate film comprising the stream, a stabilitor, through which the stream passes, located immediately adjacent to said projecting means and having its axis extending in the same direction as the line of flow of the stream.

10. In a condenser, a condensing chamber having a fluid inlet and an air outlet provided with converging walls, a rotatable impeller, located between the inlet and the outlet for projecting a stream of separate substantially flat films of liquid through the chamber and the converging outlet, the separate films comprising the stream being spaced apart and extending at an angle to the direction of their motion, and an open ended hollow cone for receiving the films discharged from the impeller, said cone being located immediately adjacent to the impeller, and having a diameter less than the diameter of the films discharged from the impeller and converging in the direction of the motion of the films.

11. In a condenser, a condensing chamber having a fluid inlet and a fluid outlet, a converging combining tube communicating with the outlet, a diffuser communicating with the outlet of the combining tube, means for projecting a stream of substantially flat liquid films through said chamber in a direction approximately at right angles to the plane of each separate film comprising the stream, and a stabilitor through which the

stream of projected films passes, for partially compressing the films and for delivering the stream to the combining tube.

12. In a condenser, a condensing chamber having a fluid inlet and a fluid outlet, a combining tube communicating with the outlet, a diffuser communicating with the outlet of the tube, means for projecting a rapidly interrupted stream of liquid moving at a high velocity into said chamber and through said combining tube and the diffuser, and a stabilitor located within said chamber between said tube and said means for receiving liquid projected from said means and delivering the liquid so received to said tube, the outlet of said stabilitor being of smaller area than the inlet of said tube.
13. In a condenser, a condensing chamber having a fluid inlet and a fluid outlet, a converging combining tube communicating with the outlet, a diverging diffuser communicating with the outlet of the tube, means for discharging a rapidly interrupted stream of liquid moving at a high velocity into said chamber and through said tube and said diffuser, and a stabilitor of less diameter than the interior of said chamber, located within said chamber between said tube and said means, for receiving liquid

from said means and delivering it to said tube, the outlet of said stabilitor being of less diameter than the inlet of said tube.

14. In a condenser, a condensing chamber having a fluid inlet port and an outlet port, a combining tube communicating with the outlet port, a diffuser communicating with the outlet of the tube, means for projecting a rapidly interrupted stream of liquid moving at a high velocity into said chamber and through the combining tube and the diffuser, and a collecting cone located within said chamber between said tube and said means for projecting liquid, said cone constituting receiving means for delivering the liquid to said tube, said cone being so located within the chamber as to provide a free fluid passage within the chamber around the cone, and the outlet of the said cone being smaller than the inlet end thereof and smaller than inlet of said combining tube.

In testimony whereof, I have hereunto subscribed my name this 26 day of April, 1910.

OTTO C. BUSS.
